UNITED STATES PATENT OFFICE.

ADOLPH JOHNSON, OF BATTLE CREEK, MICHIGAN.

ROTARY OVEN AND DRIER.

1,298,955.

Specification of Letters Patent.

Patented Apr. 1, 1919.

Application filed April 23, 1918. Serial No. 230,266.

To all whom it may concern:

Be it known that I, ADOLPH JOHNSON, citizen of the United States, residing at Battle Creek, in the county of Calhoun and State of Michigan, have invented certain new and useful Improvements in Rotary Ovens and Driers, of which the following is a specification.

This invention relates to rotary ovens and driers. More particularly, it belongs in the class with apparatus comprising an outer and usually supporting casing for a cylindrical body revolvable within the casing, and to which heat may be applied from sources also customarily within the casing. The material to be roasted or dried is admitted at one end of the cylindrical body, and discharged at the other. As ordinarily constructed the casing and the revoluble oven or cylinder are of considerable length as compared with the diameter of the cylinder.

For its object this invention contemplates the production of a rotary oven and drier falling within the type mentioned, whereof certain parts are of special construction and arrangement one with respect to another, and by which it is believed a saving of heat is effected and convenience and completeness of operation and of the desired result are increased.

The particular formation and disposition of the various parts constituting this invention are illustrated in the accompanying drawings, whereof Figure 1 represents a side view of all the parts assembled. In this view a portion of the casing and revoluble oven are broken away to shorten the view, and certain parts are shown in section, the walls of the casing and cylinder being broken away near the ends to disclose the parts located interiorly. Fig. 2 is an end view showing the right hand end of the whole structure as illustrated in Fig. 1. Fig. 3 is an end view of the left hand end of the structure as illustrated in Fig. 1.

Throughout the description and drawings, the same letter is used to refer to the same part.

Considering the drawings, the outer casing A is provided with draft dampers a in any desired number located near the bottom of the casing, and with side doors B by way of which the heating burners b, for gas, may be reached or observed. There may be any number of chimneys C, provided with dampers c, and the distance between the

chimneys may vary as set forth. It is not intended to restrict this invention to the number of gas burners, or other sources of heat, or to the precise forms of the ordinary details shown such as the dampers and doors.

Within the casing A at the left and below the end of the revolving oven, there is arranged a receiving hopper D for the cooked material, and the hopper has a spout d which passes in a downwardly inclined direction outwardly through the left hand end of the casing.

On the exterior of the right hand end of the casing A is secured a shelf E, and upon the shelf are sets of suitably supported rollers e, which will be again mentioned. In any manner, the right hand end of the outer casing is provided with a door F, by which entrance may be effected into the casing. On the left hand end of the casing is placed a shelf G, similar to the shelf E, and upon the shelf G are located the rollers g.

Considering Figs. 1 and 2, it will be noted that on the right hand end of the casing is attached a horizontal yoke or bridgepiece H, and a hopper h is supported by the yoke. The hopper h has a spout h', and near the hopper the spout h' carries a circular plate or heat barrier J, in practice usually comprising two sheets of metal spaced apart as illustrated. On the lower end of the spout h' is another similar heat guard or barrier j, which may be of larger diameter than the first mentioned. The circular barrier J fits movably within the outer end of a hollow, cylindrical gudgeon K secured to the right hand end of the oven cylinder k, and supported by the rollers e already referred to. Within the oven cylinder and mounted upon the wall thereof is a spiral vane L extending substantially from end to end of the cylinder. Near the left hand end of the oven cylinder are a number of separated openings M by which the contents of the cylinder may be discharged into the hopper D. To reach the openings M to keep them free from clogging, a door m is provided in the wall of the casing A as illustrated in Fig. 1. It will be observed that, as illustrated in Fig. 1, the heat barrier plates j and n closing the inner mouths of the trunnions K and N, have very nearly the diameter of the interior of the oven cylinder. The reason for this construction is to enable the plates j and n, in addition to their common function of

110

holding the heated air in the cylinder *k*, to prevent the flying, tumbling particles of the material treated from entering the hollow trunnions where they do not belong, and it is not desired that they should be deposited.

On the left, there is connected with the cylindrical oven and arranged centrally on the head thereof, the gudgeon or trunnion *N*. This gudgeon is closed interiorly by a double plate heat barrier *n*. The gudgeon *N* has a circumferential ridge *O* that engages corresponding grooves in the rollers *g* which rollers support the gudgeon. The ridge and grooves provided on the gudgeon and in the rollers, are to prevent the movement of the oven cylinder lengthwise as it revolves. On the trunnion *N* is mounted the gear *P*, that meshes with a pinion *Q* on a horizontal shaft *R*. The shaft and the rollers *g*, have the common bearings *r*, and the shaft is driven by the pulleys *S*, *s*, in the ordinary manner.

In the explanation of the mode of operation of this invention, it may be stated that the material to be baked or dried enters by way of the hopper *h*, and is discharged through the openings *M* in the revolving oven *k* into the hopper *D*. It is very desirable that the internal heat of the oven be maintained as far as may be without loss, therefore, the hollow gudgeons are closed by double plates in the manner described. When it is considered that the casing and gudgeons sometimes measure longitudinally together about twenty-two feet, it will be readily understood that any decided saving of the heat applied in a short time amounts to a considerable money value.

Having now described this invention, and explained the mode of its operation, what I claim is:

1. In a rotary oven and drier, the combination with an oven cylinder, of hollow trunnions arranged at the ends of the cylinder, rollers arranged to support the trunnions, a hopper having a spout extending through one of the said trunnions in a diagonally downward direction, a circular heat barrier plate located within the outer end of the trunnion, whereby the end of the trunnion is closed and the trunnion may revolve around the edge of said plate, means located beyond the end of the trunnion for supporting the said hopper and plate, and a plate attached to and supported by the spout near the lower end thereof and projecting radially beyond the sides of the trunnion in the said cylinder to close the inner end of the revolving trunnion.

2. In a rotary oven and drier, the combination with an oven cylinder, of hollow trunnions arranged at the ends of the cylinder, rollers arranged to support the trunnions, a hopper having a spout extending through the trunnion at one end of the cylinder in a diagonal downward direction, a circular heat barrier plate located in the outer end of the trunnion whereby the end of the trunnion is closed and the trunnion may revolve around the edge of the plate, means located beyond the end of the trunnion for supporting the said hopper and plate, a heat barrier plate attached to and supported by the said spout near the lower end thereof and projecting radially beyond the sides of the trunnion in the said cylinder to close the inner end of the revolving trunnion.

3. In a rotary oven and drier, the combination with an oven cylinder, of hollow trunnions arranged at the ends of the cylinder, rollers arranged to support the trunnions, a hopper having a spout extending through the trunnion at one end of the cylinder in a diagonal downward direction, a circular heat barrier plate located in the outer end of the trunnion whereby the end of the trunnion is closed and the trunnion may revolve around the edge of the plate, means located beyond the end of the trunnion for supporting the said hopper and plate, a heat barrier plate attached to and supported by the said spout near the lower end thereof and projecting radially beyond the sides of the trunnion in the said oven cylinder to close the inner end of the revolving trunnion, the said cylinder having discharge openings near the second trunnion, and a heat barrier plate arranged to close the inner mouth of the said second trunnion adjacent to the said openings.

In testimony whereof I affix my signature,
ADOLPH JOHNSON.

Copies of this patent may be obtained for five cents each, by addressing the "Commissioner of Patents,
Washington, D. C."
